UNITED STATES PATENT OFFICE.

WILLIAM A. EVERITT, OF PORTLAND, OREGON.

SNOWPLOW.

1,392,132.

Specification of Letters Patent. Patented Sept. 27, 1921.

Application filed September 16, 1920. Serial No. 410,661.

To all whom it may concern:

Be it known that I, WILLIAM A. EVERITT, a subject of the King of Great Britain, residing at Portland, in the county of Multnomah and State of Oregon, have invented certain new and useful Improvements in Snowplows; and I do declare the following to be a full, clear, and exact description of the invention, such as will enable others skilled in the art to which it appertains to make and use the same.

This invention relates to an improved snow plow of the internally heated type and one object of the invention is to provide a plow so constructed that it may be connected with a car and preferably mounted in front of the same, means being also provided to permit the plow to have vertical movement so that it will accommodate itself to unevenness in a track and so that the plow may be swung upwardly to an inoperative position when so desired.

Another object of the invention is to so construct this plow that the heating means for the same may consist of conductor pipes and discharge or burner nozzles positioned within the plow, the plow being divided into compartments through which the fuel and air pipes will pass and in which the nozzles will be positioned.

Another object of the invention is to so construct this plow that the products of combustion may pass out of the same and to further so construct it that ready access may be had to the interior of the plow for cleaning and repairing the same.

Another object of the invention is to so construct this plow that it may be connected with the rear portion of a car for trailing behind the car if so desired.

Another object of the invention is to provide a plow of this character which will be comparatively simple in construction and strong and durable.

45 This invention is illustrated in the accompanying drawings, wherein:

Figure 1 is a view in side elevation showing the plow connected with the forward end of a car.

50 Fig. 2 is a top plan view of the structure shown in Fig. 1.

Fig. 3 is an enlarged top plan view of the plow.

55 Fig. 4 is an enlarged side elevation of the plow.

Fig. 5 is a longitudinal sectional view taken along the line 5—5 of Fig. 3.

Fig. 6 is a longitudinally extending sectional view taken horizontally through the plow.

Fig. 7 is a transverse sectional view taken along the line 7—7 of Fig. 5.

Fig. 8 is an enlarged fragmentary sectional view taken longitudinally through the plow along the line 8—8 of Fig. 6.

This plow which is indicated in general by the numeral 1 is adapted for connection with the car 2 so that in the preferred form shown in Figs. 1 and 2 the plow will be positioned in front of the car and pivotally mounted for vertical swinging movement through the medium of a hinge bar 3 which extends through the bearing brackets 4 and 5 carried by the car and rear portion of the plow as shown in Fig. 2.

This plow is in the form of a hollow housing which tapers forwardly and has its forward end portion curved upwardly from the bottom thus permitting the plow to move along a track and slide easily through or over snow upon the track. Transversely extending supporting frames 6 are provided in this housing and partitions 7 which extend horizontally and are arched as shown in Figs. 5 and 8 are provided in the housing

80 and carried by the partitions so that the housing is divided into a plurality of compartments 8. These compartments are in their turn provided with dividing walls 9 thus providing auxiliary compartments 8'.

85 It should be noted that the auxiliary compartment of one compartment or chamber 8 is positioned at the opposite side of the plow from the auxiliary compartment of the adjacent compartment 8 for a purpose to be 90

hereinafter brought out.

This plow is provided in its upper wall with doors 10 which may be opened when it is desired to have access to the interior of the housing and these doors and the upper

100 wall of the housing are provided with openings having hoods 11 positioned in front of them so that the products of combustion may escape from the housing and be directed rearwardly as they pass out of the 105 housing. Openings are provided in the partitions 7 so that the products of combustion may pass from beneath the partitions into the upper portion of the plow housing and out through the openings in the upper wall

110

thereof. In order to permit the plow to have vertical movement and be swung to an inoperative position, there has been provided beams 12 which are pivotally connected with the sides of the car 2 as shown at 13 and have their forward ends connected with the arms 14 which extend forwardly in converging relation and are connected with a hanger shaft 15 which extends through the slot 16 formed in the ears 17 which extend longitudinally of the plow. It will thus be seen that with the plow in the position for use, the plow may have vertical movement to follow irregularities in the tracks and that by swinging the beams 12 upwardly, the plow may be swung upwardly to an inoperative position. In order to swing the beams upwardly, these beams have their rear end portions provided with eyes 18 which are connected with cables 19 wound upon the drums 20. By rotating the drums so that the cables are unwound from one set and wound upon the second set, the beams will be swung vertically and the plow either swung upwardly to an inoperative position or lowered to an operative position according to the direction in which the cables move. Brackets 21 are provided at the forward end portion of the plow so that if desired the plow may be connected with any suitable drag means at the rear portion of a car and thus the plow drawn after the car instead of being pushed in front of the same. This plow is to be so mounted that as it moves along the tracks, the plow may serve to push the major portion of the snow to the sides of the tracks and also serve to melt snow and ice which may remain upon the tracks beneath the plow and thus entirely free the tracks from snow. The heating means employed is in the form of liquid fuel burners having nozzles which are positioned in the compartments 8' in operative relation to the openings 23 formed in the partitions 9. It will thus be seen that the flame from the nozzles or burners 22 will be directed through the openings 23 into the compartments 8. It will be seen from an inspection of Fig. 6 that alternate burners are positioned upon opposite sides of the plow and therefore the plow will be very thoroughly heated. In order to provide oil and compressed air to the burners 22 there has been provided pipes 24 and 25 which extend longitudinally through the plow and are provided with branch pipes 26 and 27 connected with the burners. The specific construction of the burners has not been shown as any burner of the type employing fuel oil and compressed air may be employed. These pipes 24 and 25 may extend through the rear portion of the plow and are connected with feed pipes 28 and 29 which will lead to suitable reservoirs for the liquid fuel and compressed air.

When this plow is in use, it will be connected with the car in the manner shown in Figs. 1 and 2 and as the car proceeds along a track covered with snow, the plow will move the snow transversely of the track. A certain portion of the snow will tend to pass under the plow and as this snow and ice comes in contact with the hot plow the snow and ice will be melted causing the tracks to be thoroughly cleared of snow and ice. By having the plow mounted by hinges and having the arms 14 slidably connected with the plow, the plow may have vertical movement thus permitting it to follow irregularities in the track. When it is desired to swing the plow upwardly to the inoperative position, it is simply necessary to swing the beams 12 upwardly and thus cause the plow to be drawn upwardly to the inoperative position where it will be held out of engagement with the track.

I claim:

1. A snow plow adapted for hinged connection with a car for vertical swinging movement, beams adapted to be connected with a car for vertical swinging movement, arms loosely connected with the beams and pivotally and slidably connected with the plow adjacent the forward end thereof and means for swinging the beams to raise and lower the plow.

2. A snow plow adapted for hinged connection with a car for vertical swinging movement, ears carried by the plow and having slots extending longitudinally of the plow, beams adapted for connection with a car for vertical swinging movement, arms pivotally connected with the beams, a cross pin connecting the arms and passing through the slots of said ears to slidably and pivotally connect the arms with said plow, and means for swinging the arms vertically retaining the arms in an adjusted position.

3. The combination with a car, of a plow positioned in front of and hingedly connected with the car beams pivotally connected with the car for vertical movement, means for swinging said beams, and hanger means connecting the beams with the forward portion of said plow.

4. A snow plow comprising a hollow housing, fuel pipes extending longitudinally of the housing adjacent the sides thereof, and burner nozzles carried by the pipes for directing flame transversely of the housing, the burners at one side of the housing being positioned in staggered relation to the burners at the opposite side.

5. A snow plow comprising a hollow body having upper and lower chambers, the lower chamber being divided transversely into heating compartments and the heating compartments being divided into auxiliary compartments with the auxiliary compartment of one positioned at the opposite side of the

90

105

115

120

125

130

plow from the adjoining heating compartments, and heating means positioned in the auxiliary compartments for directing flame into and longitudinally of the heating compartments.

6. A plow comprising a hollow body having upper and lower chambers, the lower chamber being divided transversely to form heating compartments and the compartments being divided to provide auxiliary

compartments, air and fuel pipes passing longitudinally of the plow through the heating compartments and auxiliary compartments, and nozzles carried by the pipes in the auxiliary compartments and directing flame 15 into and longitudinally of the heating compartments.

In testimony whereof I have hereunto set my hand.

WILLIAM A. EVERITT.
